(57) **CLAIM**

The ornamental design for aircraft lavatory, as shown and described.

DESCRIPTION

FIG. 1 is a left side view of the aircraft lavatory according to a first embodiment;

FIG. 2 is a right side view of the aircraft lavatory according to the first embodiment;

FIG. 3 is a left side view of the aircraft lavatory according to a second embodiment;

FIG. 4 is a right side view of the aircraft lavatory according to the second embodiment;

FIG. 5 is a left side view of the aircraft lavatory according to a third embodiment;

FIG. 6 is a right side view of the aircraft lavatory according to the third embodiment;

FIG. 7 is a left side view of the aircraft lavatory according to a fourth embodiment; and,

FIG. 8 is a right side view of the aircraft lavatory according to the fourth embodiment.

The fragmentary showing of wood graining in FIGS. 3-8 is understood to be repeated throughout the surface(s) shown. The broken lines in the drawings depict portions of the aircraft lavatory that form no part of the claimed design. The dot-dash lines in the drawings depict a boundary of the aircraft lavatory that forms no part of the claimed design.
